THUMB TACK OR SIMILAR ARTICLE

John S. Strayer, 1006 Greenbriar Drive,
Garland, Tex. 75040

Filed Oct. 6, 1972, Ser. No. 295,589

Term of patent 14 years

Int. Cl. D8—08

U.S. Cl. D8—271

FIG. 1

FIG. 2

FIG. 3

FIG. 4

FIG. 1 is a perspective view of a thumb tack or similar article showing my new design;

FIG. 2 is an elevational view thereof;

FIG. 3 is a top plan view thereof; and

FIG. 4 is a bottom plan view of the thumb tack or similar article.

I claim:

The ornamental design for a thumb tack or similar article, substantially as shown.
